UNITED STATES PATENT OFFICE.

ALBERT G. DUNDAS, OF AGRA, KANSAS.

CASHIER'S SHIELD.

1,175,413.

Specification of Letters Patent. Patented Mar. 14, 1916.

Application filed February 13, 1915. Serial No. 7,983.

To all whom it may concern:

Be it known that I, ALBERT G. DUNDAS, a citizen of the United States, residing at Agra, in the county of Phillips and State of Kansas, have invented certain new and useful Improvements in Cashiers' Shields, of which the following is a specification.

My invention relates to cashiers' shields, and my object is to provide an apparatus of this character which can be readily installed at cashiers' cages for protection against burglary.

The invention embraces means whereby a cashier, on command of a burglar to hold up his hands, can instantly close the door and windows of his cage and thus shut out the burglar and place him at a great disadvantage.

The invention also embraces an alarm system whereby the immediate neighborhood and police headquarters is instantly notified of the attempted burglary.

The invention is well adapted for use in banks and other commercial houses where the cashier's cage is more or less exposed to burglary, and in order that said invention may be well understood, reference will now be made to the accompanying drawings, in which:

30. Figure 1 is a vertical section of a cashier's cage provided with my invention. Fig. 2 is an irregular horizontal section on line II-II of Fig. 1. Fig. 3 is a diagram of an alarm circuit used in connection with the invention. Fig. 4 is an irregular vertical section on line IV-IV of Fig. 1. Fig. 5 is a detail perspective of the shield and the customary grille placed at the cashier's window. Fig. 6 is a detail plan view of a trigger mechanism located at the door leading to the cage. Fig. 7 is a section on line VII-VII of Fig. 6. Fig. 8 is a broken detail perspective of a guideway employed in carrying out the invention. Fig. 9 is a broken horizontal section of certain parts employed in carrying out the invention.

40. A designates the cashier's cage inclosed by the usual partition B, having a door C, whereby the doorway D leading into the cage may be closed. The partition B may be of such shape as to best inclose the cage A. One corner of the partition B contains the usual cashier's window E, provided with the customary grille F. The upper portion of 50 the partition B also has the usual side win-

dows G and H, which may be inclosed either in glass or protected with grilles constructed of vertical rods I and J, respectively, to prevent a burglar from gaining access to the cage through said windows.

1 designates the shield constituting an important feature of the present invention. Said shield is made, preferably, of thin metal plate or other bullet resisting material, and is mounted in vertical guideways 2, 65 secured to the partition B adjacent the windows E, G and H.

Normally the shield 1 is held in lowered position with its upper edge approximately in line with the counter K, by latches 3, engaging lugs 3^a, fixed to the lower portion of the shield. The latches 3 are fixedly-mounted upon rock-shafts 4, 9 and 12. The rock-shaft 4 is journaled at one end in a guideway 2 and at its opposite end in a bearing 5. Said rock-shaft 4 is provided near its ends with fixedly-mounted levers 6, carrying a treadle 7 at their free ends. The treadle 7 extends approximately the length of the window G, and is normally held in raised 75 position to hold its latch 3 in engagement with its respective lug 3^a by coil springs 8 embracing the rock-shaft 4.

The rock-shaft 9 is arranged below the window E and journaled in the two adjacent guideways 2. Said rock-shaft 9 has a pair of fixedly-mounted levers 10 carrying a treadle 11 at their free ends. The rock-shaft 9 is connected to the rock-shafts 4 and 12, by arms 9^a, so that said rock-shafts will 85 operate in unison and release the latches from their respective lugs, when any one of the treadles 7, 11 and 15, is depressed. The arms 9^a are loosely connected in pairs by links 9^b, each of which has a pin-and-slot 95 connection 9^c with an adjacent arm 9^a, to allow the outer ends of each pair of arms to move toward each other as they swing downward with the treadle 7.

The rock-shaft 12 is journaled at its ends in one of the guideways 2 and a bearing 13, and like the rock-shafts 4 and 9 is provided near its ends with a pair of fixedly-mounted levers 14, carrying at their free ends the treadle 15.

From the foregoing, it will be readily understood that the latches 3 can be released from the lugs 3^a, to permit the shield 1 to rise, by depressing any one of the treadles. While in practice the springs 8 may be made 110

strong enough to sustain the weight of the treadles 7, 11 and 15, I have shown auxiliary springs 16 and 17 applied to the rock-shafts 9 and 12 to assist said springs 8 in sustaining the treadles 11 and 15, respectively.

In addition to providing means adjacent to the windows E, G, and H, for disengaging the latches 3, I have also provided means whereby said latches 3 may be released at a point distant from said windows. In carrying out said means, I employ a pedal 18 which may be located at any point within the cage A, so that the operator can release the latches 3 without going over to one of the treadles. One end of the pedal 18, is, preferably, arranged in a slot 19 in the floor of the cage and has a cable 20 attached thereto. Said cable 20 runs around guide sheaves 21 and extends up through a hole 22 in the floor, and is attached to the treadle 7. Thus when the free end of the pedal 18 is depressed, it causes the cable 20 to pull down upon the treadle 7 and release the latches 3 from the lugs 3^a. The instant the latches 3 are released from the lugs 3^a, the shield 1 quickly rises and closes the windows E, G and H.

The raising of the shield 1 may be accomplished by counter-weights or other suitable means, but in the drawings, I have shown long coil springs 23 for this purpose. Said springs 23 are housed in guideways 2. Their lower ends are secured to eyes 24 projecting from the lower portion of the shield, while their upper ends are connected to pins 25 secured to the upper ends of the guideways 2.

The upward movement of the shield 1 is stopped by two rods 26 extending from the floor to the top of the window G, where they are bent outwardly as indicated at 27 to constitute abutments for the upper edge of the shield. Rods 26, in addition to acting as stops, constitute two terminals of an electric circuit in which the shield 1 acts as a switch to close said circuit when it contacts the bent portions 27 of rods 26. Said circuit may be embraced in any one of the well-known burglar alarm systems leading to police headquarters, and embodying a gong located either inside or outside of the bank or other building provided with my invention.

In Fig. 3, I have shown a simple circuit comprising the shield 1, the rods 26, a circuit wire 29, a gong 30, a source of electrical energy 31, and a switch 32. When the shield 1 is released from the latches 3 and moves up into contact with the bent portions 27 of the rods 26, the circuit through the wire 29 is closed and sounds the gong 30, until either the shield 1 is lowered or the switch 32 is thrown open.

As disclosed by Figs. 1 and 4, the rods I and J at the windows G and H, respectively,

are vertically arranged. This prevents a burglar from holding the shield down by sticking a rod between the upper edge of said shield and the horizontal bar usually connecting the lower portions of said rods: 70 However, if it is inconvenient to dispense with said horizontal bar in the grille at the cashier's window E, I secure said grille to the shield 1, as disclosed by Fig. 5, so that it will rise with said shield and thus prevent 75 the latter from being held down by a rod or other obstacle, interposed between said shield and the horizontal bar f of the grille F.

As the door C leading to the cage A is usually left open in warm weather to aid 80 ventilation, it is desirable to have said door automatically close with the shield 1 without requiring the operator to walk over to said door for the purpose of closing the same. I accomplish this result by mounting 85 a vertical shaft 33 adjacent the hinged side of the door in bearings 34, and providing the upper portion of said shaft with a fixedly-mounted collar 35, having a notch 36 for the reception of one end of a trigger 90 37, pivoted at 38 and having its free end 39 extending into the path of the shield 1, Figs. 1 and 6. The lower portion of the shaft 33 is provided with a fixedly-mounted arm 40, the free end of which bears against 95 the door. A coil spring 41 embracing the shaft 33, rotates the same and causes the arm 38 to close the door C when the shield 1 rises and trips the trigger 35 out of the notch 36. The door 3 is provided with a 100 spring lock c, which locks the door in closed position. The door is further locked by the free end of the arm 40 entering a notch c' in said door.

From the foregoing description, it will 105 be understood that should a burglar enter the room containing the cage A with the intention of holding up the cashier, the latter can instantly protect himself by closing the door and the windows of said cage on 110 pressing downward upon any one of the treadles or the pedal, while standing or sitting with his hands raised above his head and without danger of divining his purpose to the burglar. It is also evident that when 115 thus hidden from the burglar the cashier will have full command of the situation and if he be armed, can bring said burglar down by firing through port-holes which may be provided in the lower portion of the partition.

While I have shown and described the preferred form of my invention, I reserve the right to make such changes in the construction, combination and arrangement of parts as properly fall within the spirit and scope of the appended claims.

Having thus described my invention, what I claim and desire to secure by Letters Patent, is:

1. In combination with a partition having a window therein, a grille at said window to normally close the same, a shield for closing said window and to which the grille is secured, so that the latter will be moved away from the window when the former closes said window, means to normally hold said shield open, and resilient means for closing said shield when it is released from the first-mentioned means.
2. In combination with a cashier's cage having one or more windows, a shield for closing said windows and constituting an electric switch, means to hold said shield open, means to close said shield, and an alarm circuit embodying two terminals arranged in the path of said shield so that the latter may close said circuit when closing the windows.
3. In combination with a cashier's cage having one or more windows, a shield for closing said windows, and constituting an electric switch, means to hold said shield open, rods to check the movement of said shield after the same has closed and act as electric conductors, means to close said shield, and a normally open alarm circuit connected to said rods, for the purpose described.
4. In combination with a partition having a door and one or more windows, a shield for closing said windows, and means controlled by said shield for closing the door.
5. In combination with a cashier's cage having a door and a window, a shield for closing said window, a trigger controlled by
- 5 said shield, and means controlled by said trigger for closing the door.
6. In combination with a partition having a door and a window, a shield for closing said window, means for closing the door, and means controlled by the shield for controlling the first-mentioned means.
7. In combination with a partition having a door and a window, a shield for closing said window, a shaft mounted adjacent the door, an arm on said shaft to close the door, and means controlled by the shield for controlling the operation of the shaft.
8. In combination with a partition having a door and a window, a shield for closing said window, a shaft mounted adjacent the door, means on said shaft to close the door, a spring to actuate the shaft, a collar fixed to the shaft, and means controlled by the shield to normally hold said collar from rotation.
9. In combination with a cashier's cage having a door and a window, a shield for closing said window, a shaft mounted adjacent the door, an arm on said shaft to close the door, means to rotate the shaft, a collar fixed to the shaft, and a trigger to normally hold said collar from rotation, said trigger being arranged in the path of the shield whereby it is released from the collar.
- In testimony whereof I affix my signature, in the presence of two witnesses.
- ALBERT G. DUNDAS.
